(57) **CLAIM**

The ornamental design for an camera stabilizer, as shown and described.

DESCRIPTION

FIG. 1 is a front side perspective view of a first embodiment of an camera stabilizer;

FIG. 2 is a rear side perspective view of the first embodiment of an camera stabilizer;

FIG. 3 is a front side elevational view of the first embodiment of an camera stabilizer;

FIG. 4 is a rear side elevational view of the first embodiment of an camera stabilizer;

FIG. 5 is a left side elevational view of the first embodiment of an camera stabilizer;

FIG. 6 is a right side elevational view of the first embodiment of an camera stabilizer;

FIG. 7 is a top plan view of the first embodiment of an camera stabilizer;

FIG. 8 is a bottom plan view of the first embodiment of an camera stabilizer;

FIG. 9 is a front side perspective reference view of a second embodiment of an camera stabilizer;

FIG. 10 is a rear side perspective reference view of the second embodiment of an camera stabilizer;

FIG. 11 is a front side elevational reference view of the second embodiment of an camera stabilizer;

FIG. 12 is a rear side elevational reference view of the second embodiment of an camera stabilizer;

FIG. 13 is a left side elevational view of the second embodiment of an camera stabilizer;

FIG. 14 is a right side elevational view of the second embodiment of an camera stabilizer;

(Continued)

FIG. 15 is a top plan view of the second embodiment of an camera stabilizer; and,

FIG. 16 is a bottom plan view of the second embodiment of an camera stabilizer.

The broken lines in the drawings depict features of the stabilizer that form no part of the claimed design.
